UNITED STATES PATENT OFFICE

LOUIS H. SCHWARZ, OF DETROIT, MICHIGAN, ASSIGNOR TO THE L. S. BAIT COMPANY, OF DETROIT, MICHIGAN, A CORPORATION OF MICHIGAN

SPINNER FOR TROLLING

Application filed February 18, 1928. Serial No. 255,259.

This invention relates to improvements in spinners for trolling. It is an object of the invention to provide a spinner consisting of a piece of material so flexed that it will rotate as it is drawn through the water, and which has its rear portion, to which a hook is attached, offset with regard to its front portion, so that as the spinner rotates the rear portion describes a circle having its radius substantially equal to the amount of the offset, with the result that the movement of the rear portion, as it travels, is in the form of a spiral.

Another object of the invention is to provide such a spinner which can be cheaply and easily made out of ordinary flat stock.

The construction of the spinner and its movement as it travels through the water is more fully described with the aid of the accompanying drawings, in which:

Figure 1 illustrates one view of the invention.

Figure 2 shows the blank out of which the spinner is made.

Figure 3 is a view of the spinner when turned at a different angle, and

Figure 4 is a diagrammatic view showing the path of the front and rear portions of the spinner as it is drawn through the water.

Figure 2 shows a blank of substantially uniform width throughout its entire length from which the spinner is made, and consists of front and rear portions 2 and 3 respectively connected by a laterally inclined intermediate portion 4, so that the extremities of the portions 2 and 3 while almost parallel are not in alignment with one another.

The intermediate portion 4 is flexed substantially centrally of its length transversely at 5, and the rear portion 3 is again bent at 6 in the opposite direction to counteract the inclination imparted by the bend 5. The spinner then presents the appearance shown in Figures 1, 3 and 4 according to the position from which it is viewed. 7 and 8 indicate openings in proximity to the front and rear extremities respectively, the former for a swivel connection 9 and the latter for a hook 11. 10 designates a conventional line

attached to the swivel for drawing the spinner along.

As the spinner is drawn through the water the latter exerts pressure against the surface 12 between the bends 5 and 6 and causes the spinner to turn in the direction of the arrow A. The line B indicates the path of travel of the front portion 2, and the line C indicates the path of travel of the rear portion 3 which describes a spiral movement as it is drawn through the water. The amount of the spiral movement is of course controlled by the offset distance between the extremities of the front and rear portions. It will be found that the rotation of the spinner, the two sides of which are preferably differently colored, say white on one side and red on the other, and the spiral movement of its rear portion and the hook form a very effective bait.

While in the foregoing the preferred construction of the invention has been described and shown, it is understood that modifications may be made thereto provided they fall within the scope of the appended claim.

What I claim as my invention and desire to secure by Letters Patent is:

A spinner for trolling comprising a strip-like member of uniform thickness the blank for which is substantially S-shaped, the member being flexed laterally in one direction substantially centrally of its length and in the opposite direction adjacent its rear extremity so that the front and rear portions of the member while almost parallel with one another are not in alignment with one another, the front end of said member being provided with means for attachment for a line, and the rear end of said member being provided with means for attaching a hook so that as said member is drawn through the water the front portion rotates about its longitudinal axis and the rear portion in rotating follows a sweeping spiral course the width of the path of which is twice the distance between the longitudinal axis of the front portion and the outer extremity of the rear portion.

LOUIS H. SCHWARZ.
